[57] CLAIM

The ornamental design for an animatronic toy, as shown and described.

DESCRIPTION

FIG. 1 is a top front perspective view of the animatronic toy, showing our new design;

FIG. 2 is a rear elevational view thereof;

FIG. 3 is a front elevational view thereof, with the eyes and mouth shown open;

FIG. 4 is a front elevational view thereof, with the eyes and mouth shown closed;

FIG. 5 is a side elevational view thereof, the opposite side being a mirror image, and therefore not shown; and,

FIG. 6 is a bottom plan view thereof.
